CLAIM

The ornamental design for a shoe, as shown and described.

DESCRIPTION

FIG. 1 is a front perspective view of a shoe;

FIG. 2 is a front view thereof;

FIG. 3 is a back view thereof;

FIG. 4 is a left side view thereof;

FIG. 5 is a right side view thereof; and,

FIG. 6 is a top view thereof.

The evenly-spaced broken lines in the drawings depict portions of the shoe that form no part of the claimed design. The stitching on the shoe forms no part of the claimed design.

1 Claim, 4 Drawing Sheets
